YARN CARRIER CONTROLLING MECHANISM

Filed March 4, 1930

UNITED STATES PATENT OFFICE

1,926,535

YARN CARRIER CONTROLLING
MECHANISMEdgar F. Hathaway, Wellesley, Mass., assignor
to Shawmut Engineering Company, Dorchester,
Mass., a corporation of Massachusetts

Application March 4, 1930. Serial No. 433,004

5 Claims. (Cl. 139—7)

My present invention relates to pile fabric looms, such as carpet looms, and more particularly aims to provide improved means for conveying the yarn carriers or tube frames and for presenting them successively in operative position.

In the drawing illustrating one form of mechanism embodying the invention,

Fig. 1 is a partly diagrammatic side elevation 10 of portions of a loom and of the yarn-carrier or pattern chain mechanism therefor;

Fig. 2 is a plan view, upon a larger scale, of a short section of a carrier chain;

Fig. 3 is a side elevation of the chain shown in 15 Fig. 2, looking at the inner side of the chain;

Fig. 4 is an elevation upon an intermediate scale, showing a section of a vertical run of the chain with supported tube frames or yarn carriers, parts of the frame-attaching means being 20 in vertical section;

Fig. 5 is a partial section on the line 5—5 of Fig. 1 and illustrating the chain and an attached frame as positioned during a horizontal run of the chain; and

Fig. 6 is a vertical section showing certain frame-guiding and positioning means at the operative or transfer position of the tube frames or carriers.

Referring to Fig. 1, a portion of one loom side 30 is seen at 1. The carrier or pattern chain is supported upon a framework including the uprights 2 and the top beam 3, similar members being also provided at the opposite side of the loom.

A chain such as generally employed in this connection is made up of alternate single links 4, 35 see Figs. 2 and 3, and double links 5. It passes over upper guide wheels or sprockets, one of which is seen at 6 in Fig. 1, down around a similar sprocket 7 at the operative or transfer position, and which is usually a driven element, and is looped around series of intermediate and lower guide pulleys or wheels 8 and 9. It is caused to travel, step by step, in either direction 40 as the pattern requirements dictate, to bring the yarn carriers or frames successively to their operative or transfer position, at the lower left portion of Fig. 1.

The tube frames or yarn carriers, as best seen 50 in Figs. 4 and 5, comprise longitudinal bars or frames proper 10 carrying a series of tuft yarn guides or tubes 11 for the yarns or spools 12 journaled in spool brackets 13 on the frames. The term "frame" or "yarn frame" is hereafter used in the description and claims to refer generically to any form of element for supporting and directing a series of yarn units in this art. The frames are adapted for supporting attachment to the pattern chains, herein releasably, by suitable suspension means at the frame ends, com-

monly termed ears or brackets. These may be of various forms, such for example as in my Patents Nos. 1,528,611, 1,621,406 or others. As herein shown they include an offset arm or bracket 14 and a cooperating movable latch or hook 15.

In existing practice the suspension element or frame ear is usually connected to the chain by entering the arm 14 directly between the sides of a double-link unit 5 and engaging the latch or hook 15 over one edge of the link. The frames are thus held with their tubes or yarn guides substantially perpendicular to the chain at all times. Thus throughout a horizontal run the frames stand substantially upright, while in vertical runs they project outwardly from the chain approximately horizontally or somewhat below the horizontal. However, the frames are required to be readily releasable from the chains for transfer into the loom and considerable play is necessarily present between the frame ears and the engaged chain link. This frequently occasions an objectionable swinging or flopping of the frames from one angle to another relative to the chains, particularly where they pass from a horizontal to a vertical run or vice versa. Such flopping over of the frames is sometimes so violent as to cause the frames to become disengaged from the chain or to dislodge yarn spools from their frames, with resultant costly delays in the weaving operations and possible great damage to the loom.

In a copending application Serial No. 433,003, filed March 4, 1930 I have disclosed and claimed means whereby this objectionable feature is obviated by supporting the frames while permitting them to shift gently from one to another angle relative to the chain. My present invention, while dealing with the same general problem, removes the cause of the abrupt violent shifting of the frames on the chains, by making them self-positioning relative thereto and enabling them always to retain a given angle with respect to the true vertical, regardless of their position along the chain, whether in a horizontal or in a vertical run.

In the present embodiment of the invention the frames 10, are rotatively associated with the chains about axes parallel with the frames themselves. As best seen in Figs. 2 and 3, I herein provide rotatable or swiveled members or frame receivers 16 on the chains at the points where frames are to be attached. Each such frame receiver 16 as a whole may be generally similar to a double-link unit of the chain and as shown comprises two longitudinal plates 17 separated by spacers 18, which may be separately formed or integral with the plates 17, as preferred. The plate 17 adjacent the chain proper carries centrally thereof a journal 19 projecting through

bearing apertures 20 in the links of the double chain units 5. A collar 21 at the base of the journal 19 holds the frame receiver properly spaced from its supporting chain link.

5 It will be understood that similar sprockets and chain mechanism are provided at the opposite side of the loom as that shown in Fig. 1, the frames 10 being supported by and between the receivers on the chains at the two loom sides.

10 Where frames of the same standard lengths as heretofore are to be employed, the spacing between the sprockets and chains at the opposite loom sides is made such as to bring the frame receivers, shown at the inner face of the chains, 15 into proper alignment with the frame ears or brackets.

Through the described means, the tube frames or yarn carriers 10 are adapted to remain in substantial parallelism with themselves throughout 20 their entire extent of travel. Their position assumed in the illustrated form of the invention is with their yarn tubes or guides 11 pointed downward, in the same position in which they are required to be for presenting their yarns to the 25 warp. This pendant position of the frames is automatically assumed and maintained, the center of gravity of the frames being below their axis of rotative association with the chains.

When the frames are traveling on a horizontal 30 run of the chain, as at the top in Fig. 1, also in Figs. 2 and 3, and as shown in section in Fig. 5, it will be seen that the frame receivers 16, while always remaining substantially horizontal, are then parallel with the chain proper. As the 35 frames pass about the sprocket or guide wheel, a relative turning movement takes place between the supporting links and the frame receivers, in one or the opposite direction depending on the direction of chain travel, until in an ensuing vertical run the links are substantially at right 40 angles to their supported frame receivers, as clearly seen in Fig. 4.

Means desirably is provided adjacent the operative or presenting position of the frames 10 to 45 bring them to and hold them in proper position for cooperation with the transfer mechanism of the loom. As illustrated at the lower left portion of Fig. 1 and in detail in Fig. 6, this means herein comprises a horizontal arm or positioner 50 23 on a bracket 24 attached to a convenient fixed part of the loom, and preferably duplicated at the other loom side. Each positioner is proportioned and located to lie in the path of the adjacent chain and of the outer portion of the 55 frame receivers 16 thereon as the frames reach the bottom of the loop of chain at the left in Fig. 1, the point at which they are taken from the chain by the transfer mechanism or so called transfer cams and returned thereto. The under 60 surface of the frame receiver 16 supporting the frame then in operative position seats upon the upper face of the positioner 23 and is thus positively prevented from turning, accurately positioning and holding the frame. The free end of 65 the positioner is preferably somewhat downturned, as indicated at 25, Fig. 1, to insure proper reception and subsequent disengagement of the succeeding frame receivers.

Because of the fact that the frames as illustrated are supported by means spaced from the 70 links of the chain proper, it becomes possible to

support and guide the chain proper across its entire width. For example, as seen in Figs. 1 and 5, a guide bar or way 27 desirably is provided, mounted on posts 28 disposed at suitable intervals along the chain-supporting framework. This 80 guide or way 27, as shown, is of sufficient width to extend entirely across below the chain, which moves along and is supported and guided on the upper face of the way. The posts 28 preferably have upwardly extended portions or fingers 29 which serve to guide the chain laterally, that is, lengthwise of the yarn carriers or tube frames, thus further insuring proper movement thereof and accurate alignment between the entire series 85 of supported frames.

90 In certain of its aspects my invention is also applicable to looms wherein the yarn frames are not removed from the chains during weaving.

95 My invention is not limited to the particular embodiment thereof herein illustrated and described, its scope being set forth in the following claims.

I claim:

1. In a tuft-fabric loom, in combination with the pattern chains and their supporting mechanism, a plurality of yarn frames, means on the chains whereby the frames are rotatively supported on and between the chains, and means adjacent the operative or transfer position of the frames to engage and restrain said means on the 100 chains thereby to position and hold a frame for transfer.

2. In a tuft-fabric loom, in combination with the pattern chains and their supporting mechanism, a plurality of yarn frames, rockable receivers on the chains to support the frames, and positioning means at the frame transfer point to hold the receivers of a presented frame against rocking. 110

3. In a tuft-fabric loom, in combination with the pattern chains and their supporting mechanism, a plurality of yarn frames having suspension elements each including an offset arm and movable latch, and receivers on the chains for said suspension elements, each comprising a pair of spaced plate members adapted to receive the 120 offset arm of a frame suspension element between them and to receive the cooperating latch of said suspension element, and means intermediate the ends of said members connecting them to the adjacent chain link for movement relative to the 125 latter.

4. In a tuft-fabric loom, in combination with the pattern chains and their supporting mechanism, a plurality of yarn frames, means on the 130 chains, carried by but in addition to and offset from the links themselves, for supporting the frames by engagement therewith in planes parallel to but spaced from the longitudinal vertical planes of the chains proper, and chain-guiding means cooperating with the under faces of the 135 chain links in said longitudinal planes of the chains proper.

5. In a tuft-fabric loom, in combination, pattern chains comprising hingedly connected links, means rotatively carried by some of the links for detachably receiving latch-type suspension elements of yarn frames, and positioning means on the loom to hold said rotative means in given angular position on and with respect to the pattern chains at desired times. 140
